COMBINED WARDROBE AND CLOTHES RACK

Ada G. Ellison, Montgomery, Ala.

Application October 12, 1956, Serial No. 43,335

Term of patent 14 years

(Cl. D33—19)

FIG. 1.

FIG. 2.

Figure 1 is a perspective view of a combined wardrobe and clothes rack showing my novel design, looking down at upper corner thereof; and

Figure 2 is a perspective view looking at the side opposite that of Figure 1, looking up at a lower corner of the combined wardrobe and clothes rack showing my new design.

I claim:

The ornamental design for a combined wardrobe and clothes rack, as shown.
